UNITED STATES PATENT OFFICE.

PRESTON C. DOCKSTADER, OF COLORADO SPRINGS, COLORADO.

LOCK-RAIL JOINT.

SPECIFICATION forming part of Letters Patent No. 462,399, dated November 3, 1891.

Application filed October 25, 1890. Serial No. 369,826. (No model.)

To all whom it may concern:

Be it known that I, PRESTON C. DOCKSTADER, of Colorado Springs, in the county of El Paso and State of Colorado, have invented 5 certain new and useful Improvements in Lock-Rail Joints; and I do hereby declare that the following is a full, clear, and exact description thereof, reference being had to the accompanying drawings, and to the letters of reference marked thereon, which form a part of this specification.

This invention relates to new and useful improvements in the construction of devices for locking the ends of railroad-rails together, 15 wherein a "chair" is used, within or upon which the adjacent ends of two rails are placed and to which said rails are secured.

The invention consists in the matters hereinafter described, and pointed out in the appended claims.

In the accompanying drawings, illustrating my invention, Figure 1 is a perspective view of a chair embodying my invention with the adjacent ends of two rails locked in position 25 therein. Fig. 2 is a side elevation of the same. Fig. 3 is a perspective view, partly in section, the sectional portion of said view being taken on line 3 3 of Fig. 2. Fig. 4 is a separate perspective view of one of the wedges employed 30 to retain the ends of the rails in proper position within the chair. Fig. 5 is a perspective view of the chair, illustrating the manner in which the under side of said chair is formed. Fig. 6 is a bottom plan view illustrating a 35 modified form of the same. Fig. 7 is a perspective view illustrating another modification. Fig. 8 is a central vertical section taken on line 8 8 of Fig. 1. Fig. 9 is a perspective view of a chair, showing a different method 40 of securing the wedges in place. Fig. 10 is a separate view of the key.

In said drawings, A A indicate the adjacent ends of the rails, and B a chair of wrought or cast iron, steel, or other suitable material. 45 The chair B is formed with a flat surface b, upon which the ends of the rails rest. The chair B is also formed with two upwardly-projecting flanges B' B', suitably shaped, to embrace the lateral flanges a a upon the base 50 of the rails and engage at their upper edges against the under side of the heads a' a' of the rails adjacent to the webs of the latter.

These flanges B' B' are curved or deflected inwardly, so as to approach the webs of the rails above the flanges a a at the bottom of 55 the rails, and are then directed upwardly and inwardly, so as to engage the webs of the rails adjacent to the head of the latter.

The chair is designed to be placed upon and secured to the railroad-tie, and for this 60 purpose holes C C are formed in said chair at convenient locations, through which spikes are driven into the tie to secure said chair in place thereon.

Upon the flat face b of the chair and at the 65 sides thereof upon which rest the flanges a a of the rails are formed upwardly-projecting studs or lugs b' b', adapted to engage corresponding notches a² a² in said flanges a a to prevent the rails from shifting longitudinally 70 within said chair. The space between the inclined portions of the flanges B' B' of the chair B and the horizontal surface b is made sufficiently great to permit the flanges a a at the base of the rails to be inserted under said 75 flanges and above said studs b' b' and moved longitudinally within said space until the notches a² a² coincide with said studs when the rail is dropped down, so that the studs will engage said notches and retain the ends 80 of the rails in place within the chair. The under or inside surfaces of the flanges B' B' are preferably somewhat inclined from end 85 to end, so that the space between each of said flanges and the horizontal surface b is somewhat greater at one end than at the other, and when the rails are properly adjusted tapered wedges E E are driven into said spaces above the flanges a² a² and between said 90 flanges a² a² of the rails and the flanges B' B' of the chair, so as to prevent displacement of the rails. The wedges E E are preferably of 95 such shape in cross-section as to conform to the shape of the rail at the base of the web, so as to firmly brace the rails against lateral strain. The form of said wedges is clearly shown in Figs. 1, 2, 4, and 8, and, as shown in said figures, a longitudinal rib e may be provided along the upper edge of each of said wedges, said ribs being adapted to engage the 100 angles formed by the bend in the flanges B' B' and operating to more firmly crowd said wedges against the webs of the rails when they are driven into position within the chair.

The under surfaces of the flanges B' B' are inclined in such manner that the larger or deeper portion of the space beneath one of said flanges will be at one end of the chair and the large 5 or deep part of the space beneath the other flange will be at the other end of the chair, so that the wedges E E may be driven into said spaces from opposite ends of said chair. By this construction a very firm and even 10 pressure is brought upon the rails, and any strain which would tend to loosen one of the wedges would obviously tend to tighten the other, so that the liability of the rails "creeping," so common in joints of this character, 15 is very greatly lessened. The chair is also formed with one of its sides, preferably the side designed to come upon the outer side of the rails, or that next the end of the tie when in use, extended or prolonged in a direction 20 at right angles to the rails, as shown in the drawings at B², so as to provide additional strength at the outside of the chair to prevent the liability of the rails spreading and to afford a more stable support for the same. In 25 order to further strengthen said outer portion of the chair, I provide a rib or brace B³, extending from near the top of the outer flange B' downwardly and outwardly along the extended portion B² of the chair.

30 As a separate and further improvement, in order to more securely hold the chair in position upon the tie, I provide one or more ribs or flanges D upon the under side of the chair, as shown more particularly in Figs. 5 and 6. 35 These ribs are formed with sharp edges, so that when the chair is placed upon the tie and spikes driven through the holes C C to secure the chair in place as the spikes are driven home the ribs D D will be forced into 40 the upper surface of the tie. In this manner the ribs afford an additional support to prevent the chair from shifting from its proper position upon the tie and relieve in a great measure the strain upon the spikes. The ribs 45 D D may be arranged in any preferred manner upon the under side of the chair, either as shown in Fig. 5 or in Fig. 6 or otherwise, as desired.

Instead of the ribs D D, a number of pointed 50 studs, as d d, Fig. 7, may be formed upon the under side of the chair, which will of course operate to retain the chair in position upon the tie in the same manner as the ribs D D.

By reference to the drawings it will be observed that the bolt-holes are all inclosed instead of being arranged in the form of notches cut in the margins of the chair, as in the forms 55 of chairs heretofore commonly in use. By this construction the chair is much more firmly 60 retained in position on the tie, and there is no liability of its becoming loosened, as sometimes occurs in the use of open notches by reason of one or more of the spikes being bent outwardly until free from said notches.

65 The horizontal surface of the chair between the flanges B' B' is preferably hollowed out or grooved at its central part, as shown at b²

in Figs. 2, 3, 5, 7, and 8 of the drawings, so that the side flanges a a of the rails will rest evenly upon the surfaces b b at each side of 70 the chair. By this construction the strain is uniformly distributed throughout the chair and is not concentrated at a point directly beneath the web of the rail, as would be the case if the groove b² were not present. 75

As a separate and further improvement, I provide each of the wedges E E with one or more grooves or slots e' e' at its smaller end, said slots or grooves extending crosswise of the wedge, as shown more particularly in 80 Fig. 4 of the drawings. The wedges are made of sufficient length to project at their smaller ends somewhat beyond the ends of the chair when driven into place therein, as shown in Fig. 1. 85

In order to secure the wedges firmly in position and prevent accidental displacement of the same, I drive into one of said slots e' e', adjacent to the end of the chair, a key or cotter e², the same being of sufficient thickness 90 to cause it to project above the surface of the wedge and prevent the same from moving longitudinally within the chair. I find in practice that an ordinary wrought nail is well adapted for this purpose. 95

In order to prevent the key or cotter from working out of the slot in the wedge, I form the end of the chair with a projecting ear b³, arranged to extend over said slot and against which the key bears when driven, so as to prevent the key from being raised out of engagement with said slot. As the said key is driven into the slot it strikes against the web of the rail and its end is turned upwardly, as shown in Fig. 2, so that it is prevented from working backwardly out of the slot by its bent end coming against the projecting ear b³. The ear b³, formed as herein described, is, however, not essential, inasmuch as other equivalent devices may be employed to hold 100 said key in position—as, for instance, as shown in Fig. 5, a shallow recess or groove b⁴ may be formed in the end of the chair and the key be driven into position within said recess, taking in such case an inclined direction in entering the slot, but being straightened out in passing through the same, its end being bent upwardly upon striking the rail-web, as before described. In this form of construction 110 it is obvious that the upper surface of the recess bears upon the top of the key or cotter in precisely the same manner as does the projecting ear or lug and serves to retain the key 115 in place within the groove. 120

A main advantage gained by my improved 125 construction in locking devices for securing the adjacent ends of the rails together is that no bolts are used in forming the joints, and at the same time the rail ends are firmly locked in position by the wedges and are 130 strongly braced from different directions by the flanges upon the chair.

One cause of "creeping" of the rails is that the grip of the bolts is often unequal—that is

to say, it is very difficult and often impossible to adjust a bolt so that it presses the splice against the end of one of the rails with a pressure equal to that exerted by other bolts 5 in the adjacent end of the other rail and in the same joint—and it follows that while one rail is gripped very firmly the other rail in the same joint may be comparatively loose, so that the rolling blow from a passing train 10 will cause the loose rail to act against its neighbors as a sledge-hammer and drive them in either direction, thus causing creeping of the track. It is obvious, however, that by my improved construction a very even, strong, and 15 vise-like grip upon the ends of both rails is produced, and the wedges being driven into position from opposite directions firmly secure the ends of the rails from longitudinal movement in either direction. Furthermore, the bottom 20 flanges being gripped within the chair at a point remote from the web or center of the rail, and the chair being cut away or grooved beneath the center of the rail, a very even distribution of the strain is attained and the 25 joint is rendered somewhat elastic and the liability of breakage caused by the excessive rigidity of the so-called "dead-joints," or joints in which there is no elasticity of the rails or chair, is materially decreased. Furthermore, by my improved construction, the 30 joint being short and an even vise-like grip taken of the rails from opposite directions, in case of a low joint the rails will spring on either side of the joint and bend bow-shaped, 35 the same as in the center of the rail, and will spring back into position again after the train has passed, thus avoiding trouble and expense from bent rail ends, it being a well-known fact that with bolt-joints the ends of 40 the rails are liable to bend into a V shape and remain so, thus injuring the rail.

By my construction as herein described an exceedingly strong joint is provided and practically a continuous rail is obtained.

45 It is obvious that instead of the key shown in Figs. 1 and 2 different forms of keys may be employed--as, for instance, the form shown in Figs. 9 and 10, in which the key is formed from a piece of wire bent into the form shown 50 in Fig. 10. The wedge is formed in the same manner as before, having the transverse grooves e' across its upper surface, and the key F being formed with a straight portion f , adapted to engage one of said grooves e' , 55 and having its ends bent at right angles to the straight portion f , so as to project beneath the flange B' of the chair to hold the straight portion f in engagement with the groove e' . In this form of key one end, as f' , 60 is preferably formed with a V-shaped bend and the other end f^2 is left straight.

In use the V-shaped end f' of the key is inserted between the web of the rail and the upwardly-projecting part of the flange B' 65 above the wedge, and the end f^2 is inserted under the inwardly-projecting portion of said flange B' at the side of the wedge. The key

is then driven into position, as shown in Fig. 9, the straight part f engaging with one of the transverse grooves e' and operating to retain 70 the wedge in place in the chair in precisely the same manner as the key shown in Figs. 1 and 2. It is obvious that the bent ends $f' f^2$ will when the key is in position exert a downward pressure upon the straight portion f and effectually prevent any displacement of the key. Where this form of key is employed the chair may be recessed or not, as desired, the particular form shown being without either the recess or the projecting ear shown 80 in the other figures of the drawings.

I claim as my invention—

1. The combination, with the track-rails, of a chair having a horizontal base supporting the adjacent ends of said rails and provided 85 with two upwardly-projecting flanges embracing the bottom flanges of the rails and engaging at their upper edges with the webs of said rails, and tapered wedges inserted between said flanges upon the chair and the bottom 90 flanges of the rails, said wedges being provided with transverse grooves, and keys or cotters adapted to be inserted in one of said grooves of each of said wedges and to engage the chair to prevent longitudinal movement 95 of said wedges, substantially as described.

2. The combination, with the track-rails, of a chair having a horizontal base supporting the adjacent ends of said rails and provided 100 with two upwardly-projecting flanges embracing the bottom flanges of the rails and engaging at their upper edges with the webs of said rails, and tapered wedges inserted between said flanges upon the chair and the bottom 105 flanges of the said rails, said wedges being provided with transverse grooves, and keys or cotters adapted to be inserted in one of the grooves of each of said wedges and to engage the chair to prevent longitudinal movement of said wedges, said chair being also provided 110 with overhanging portions adapted to bear upon the upper side of said keys or cotters, substantially as described.

3. The combination, with the track-rails, of a chair having a horizontal base supporting 115 and bearing against the bottom flanges of said rails and provided with two upwardly and inwardly extending flanges embracing the bottom flanges of the rails and bearing against the webs of the rails at their upper edges, said 120 flanges having the lower surfaces of their inwardly-extending portions inclined from end to end, and tapered wedges inserted between said flanges and the bottom flanges of the rails, said wedges being each formed with a 125 rib extending along its upper edge and adapted to engage the angle formed by the bent portion of the flange, said wedges being also provided with one or more transverse grooves, and keys adapted to be inserted in one of said 130 grooves of each of said wedges, substantially as and for the purposes set forth.

4. The combination, with the track-rails, of a chair having a horizontal base supporting

the adjacent ends of said rails and provided with two upwardly-projecting flanges embracing the bottom flanges of the rails and engaging at their upper edges with the webs of said rails, and tapered wedges inserted between said flanges upon the chair and the bottom flanges of the rails, said wedges being provided with transverse grooves, and keys or coppers adapted to be inserted in one of said grooves and to engage the chair to prevent longitudinal movement of said wedge, said

chair being provided with projecting ears or lugs adapted to bear upon the upper side of said keys or coppers, substantially as described.

In testimony that I claim the foregoing as my invention I affix my signature in presence of two witnesses.

PRESTON C. DOCKSTADER.
